HAIR WAVING APPARATUS

Peter Santurello, Columbus, Ohio

Application September 23, 1932, Serial No. 634,574

32 Claims. (Cl. 132—33)

My invention relates to hair waving apparatus. It has to do, more particularly, with the provision of a device upon which the hair may be wound and tightened as a preliminary step in the permanent wave hair dressing process.

One of the objects of my invention is to provide a hair waving apparatus of the type indicated which is comparatively simple and which is extremely effective for the purpose intended.

10 Another object of my invention is to provide a device of the type indicated having an easily manipulated gripping and locking device for attaching the mandrel to a lock of hair adjacent the scalp in such a manner that it will not be 15 injurious to the hair.

Another object of my invention is to provide a device of the type indicated which is of such a character that the hair may be wound on the device in various ways so that various types of 20 waves may be produced.

Another object of my invention is to provide a device of the type indicated having means for placing all parts of the hair, wound upon the mandrel, under substantially equal tensional 25 strains, such means being of such a type that, during the stretching of the hair on the mandrel, no portion of the hair will be subjected to excessive strains thereby causing injury thereto.

In its preferred form, my invention contemplates the provision of a hair-waving device having a mandrel on which the hair is adapted to be wound. This device is provided with a member which is adapted to secure the free end of the lock of hair to the mandrel. As will be explained 30 more fully hereinafter, the winding of the hair on the mandrel is begun on the free end of the lock of hair and such hair is wound thereon until a point adjacent the scalp is reached. When 35 this point is reached that portion of the lock of hair adjacent the scalp is inserted in the locking means mounted adjacent the lower end of the mandrel. This locking means is then operated to tightly grip the hair. The device is also provided with means for tightening the hair on the mandrel and for subjecting all portions of the lock of hair to substantially equal tensional stresses. 40 This tightening means is of such a type that, during the tightening of the hair on the mandrel, no portion of the lock of hair will be subjected to excessive tensional strains which would cause 45 injury thereto. My device is further provided with means for maintaining the hair in tightened condition on the mandrel during the subsequent dampening and heating or steaming operations of the permanent waving process.

Other objects and advantages will appear as this description progresses and from the appended claims.

The preferred embodiment of my invention is shown in the accompanying drawings wherein 5 similar characters of reference designate corresponding parts and wherein:

Figure 1 is a perspective view of a hair curling device made in accordance with my invention.

Figure 2 is a perspective view of my hair-waving device showing the various parts thereof disassembled and in spaced cooperative relation.

Figure 3 is a detail in perspective of the upper end of the shaft on which the various parts of my device are mounted and also showing a gear 15 which is adapted to be mounted on the upper end thereof.

Figure 4 is a detail in perspective, partly broken away, showing the locking device which is adapted to lock the mechanism, which is used 20 for tightening the hair on the mandrel, in any position to which it is adjusted.

Figure 5 is a longitudinal section taken through my hair-waving device.

Figure 6 is a detail in section showing the upper portion of my hair-waving device, the various parts being shown in the positions they occupy when it is desired to tighten the hair on the mandrel.

Figure 7 is a view similar to Figure 6 and showing the various parts of my device in the positions which they occupy when the mechanism for gripping the lock of hair adjacent the scalp is adapted to be operated.

Figure 8 is a bottom plan view of my hair-waving device showing the mechanism for gripping the lock of hair and holding it on the mandrel.

Figure 9 is a perspective view showing the initial operation in applying a lock of hair to my hair-waving device.

Figure 10 is a perspective view showing a lock of hair wound on my device and showing how that portion of the hair adjacent the scalp is inserted in the locking means, adjacent the lower end of the device, which is adapted to tightly grip and hold the hair on the mandrel.

Figure 11 is a view similar to Figure 10 showing how the tightening mechanism of my device is operated to cause the lock of hair to be secured 50 on the mandrel in stretched condition.

Figure 12 is a view similar to Figure 11 showing a tube, having material therein which is saturated with hair-waving solution, placed over my device.

Figure 13 shows a type of heater in which my hair-waving device may be placed.

Figure 14 is a detail, partly in section, showing the upper portion of the heater shown in Figure 13.

With reference to the drawings, my invention is shown as comprising a mandrel 1, upon which the hair is adapted to be wound. This mandrel preferably comprises a body portion of substantially the shape shown in the drawings, which consists of a central portion 2 which is of comparatively less cross-section than the end portions 3 and 3'. As will be readily apparent from the drawings, the outer surface of the mandrel 15 gradually flares outwardly from a central portion to each end thereof. In Figures 2 to 7, my device is shown in horizontal position but it will be apparent that the end of the device at the right is the upper end while the other end is the end 20 which will be disposed adjacent the scalp.

The mandrel 1 is provided with a cylindrical extension 4 on the upper end thereof. This cylindrical extension 4 is provided with a longitudinal slot 5 formed in the outer surface thereof. This slot 5 is adapted to receive a key 5' which is disposed on the inner surface of a collar 6 mounted in surrounding relation to the extension 4. Thus, this collar 6 is splined on the cylindrical extension 4 and can be moved longitudinally 30 thereof but cannot be rotated thereon.

A member 7 which is adapted to grip the free end of the lock of hair and hold it on the body portion of the mandrel 1, is pivotally connected to the collar 6. This member 7 is bifurcated at 35 its upper end and the arms 8 thereof, are adapted to fit around the collar 6 and to be pivotally connected thereto by pins 9 passing through openings therein. The member 7 is of such a shape that it will fit over the mandrel 1 and will extend 40 substantially half-way therearound.

As will be understood hereinafter, the free end of the hair is placed on the mandrel and the member 7 is then swung down over the mandrel to grip the hair thereto. The member 7 may be 45 moved longitudinally relative to the mandrel 1 by moving the collar 6 back and forth on the cylindrical extension 4. Thus, the member 7 may be moved to any desired longitudinal position relative to the mandrel 1. As will be seen 50 from Figure 5, a shoulder 10 is provided on one side of the body portion of the mandrel 1 at the upper end thereof, to prevent the collar 6 slipping downwardly thereover. However, this shoulder only extends a very short distance around the 55 mandrel and is disposed diametrically opposite to the point where the collar 6 is splined to the extension 4 so that the member 7 may be moved downwardly into firm contact with the body portion of the mandrel, no matter what longitudinal 60 position it occupies relative thereto.

The upper end of the cylindrical extension 4 is provided with teeth 11 integrally formed thereon. These teeth are provided for a purpose to be later explained. The main body portion of the mandrel and the cylindrical extension 4 are provided with a centrally disposed opening 12 extending entirely therethrough. The lower end of the mandrel 1 is provided with a cylindrical socket member 13 suitably formed therein, for a purpose 65 which will be hereinafter described.

The opening 12 is adapted to receive a shaft 14 which is adapted to extend entirely therethrough and to project from each end of the mandrel 1. The shaft 14 has a cup-shaped member 15 keyed 70 thereon adjacent the lower end thereof. This

member 15 is adapted to be rotated by rotation of the shaft 14. The member 15 comprises a bottom 16 and an upwardly projecting flange 17 integrally formed thereon. This flange 17 is also flared outwardly as will be obvious from the drawings. The bottom 16 and the flange 17 are cutaway as at 18 so that a lock of hair may be passed therethrough. The bottom 16 is also provided with a spiral slot 19 which extends from the cutaway portion 18 a substantial distance 10 around the bottom 16 and to a point adjacent the center thereof (Figure 8). This slot 19 communicates with the cutaway portion 18 and is comparatively wide at this point. The slot 19 gradually decreases in width from its outer end 15 adjacent the cutaway portion 18 to its inner end adjacent the center of the bottom 16 of member 15. The flange 17 is also provided with a finger 20 integrally formed thereon which projects out into the cutaway portion 18. 20

As shown in Figures 2 and 5, the shaft 14 projects for a short distance below the bottom 16 of the member 15. This shaft is threaded at its lowermost end as at 21. The lower end of the shaft 14 is adapted to pass through an opening 25 23 in a second cup-shaped member 22. The member 15 is adapted to fit within the member 22 and to be rotatably mounted therein. A removable nut 24 is adapted to cooperate with the threaded lower end 21 of the shaft 14 to maintain the member 15 within the member 22.

The member 22 comprises a bottom 25 having an upwardly extending annular flange 26. This flange is also flared outwardly and is adapted to lie in close contact with the flange 17 of the member 15 when such member is mounted in the member 22. The bottom 25 and the flange 26 are cutaway as at 27 and this cutaway portion may be brought into coincidence with the cutaway portion 18 of the member 15 when this member 40 15 and the member 22 are brought into a certain position relative to each other (Figure 8).

The outer surface of the member 22 is provided with a plurality of lugs 28 suitably formed thereon. By means of these lugs the member 22 may 45 be firmly held while the member 15 is rotated therein through the medium of the shaft 14 and other mechanism to be later described. The flange 26 is further provided adjacent its upper edge with a notch 29 cut therein. The finger 20 50 of flange 17 of member 15 is further provided with a shoulder 20' formed on its upper edge. This notch 29 and shoulder 20' are provided for a purpose which will be subsequently described.

A third cup-shaped member 30 is loosely 55 mounted on the shaft 14 above the cup-shaped member 15. This cup-shaped member 30 comprises a bottom portion 31 and an upwardly extending and outwardly flared flange 32 integrally formed thereon. This flange is bent outwardly at 60 its upper edge and then downwardly to form an annular groove 33 extending almost entirely around the upper end of the member 30. The bottom 31 and the flange 32 of the member 30 are also provided with a cutaway portion 34. This 65 cutaway portion 34 always lies in coincidence with the cutaway portion 27 in the member 22, and the cutaway portion 18 of the member 15 may be brought into coincidence with both the cutaway portions 27 and 34 when desired so that 70 a lock of hair may be passed through this gripping and locking mechanism.

As shown in Figure 5, when the gripping device is assembled the cup-shaped member 15 will fit within the cup-shaped member 22. Fur- 75

thermore, the cup-shaped member 30 will fit within the cup-shaped member 15. The upper edge of the flange 17 of the cup-shaped member 15 will fit in the groove 33 formed on the upper portion of the member 30. A pin 35 extends transversely across the groove 33 and this pin is adapted to cooperate with the notch 29 formed in the upper edge of the flange 26 to prevent relative rotation between the member 22 and the member 30. Thus, the cutaway portions 27 and 34 of the members 22 and 30 respectively will always lie over each other.

The bottom portions and the side walls of all the cup-shaped members 22, 15 and 30 will all lie in close contact. However, the member 15 will be rotatably mounted between the cup-shaped member 22 and the cup-shaped member 30, as will be readily apparent. The shoulder 20 on the upper edge of flange 17 of member 15 will cooperate with the pin 35 to limit rotation of the member 15 in either direction.

When it is desired to use the gripping device the various parts of this mechanism are adjusted to the positions shown in Figure 8. A lock of hair is then segregated and is passed through the cutaway portions 34, 18 and 27 in the members 30, 15 and 22 respectively. With the hair so positioned the member 15 is then rotated in a clockwise direction (Figure 1) which will cause the finger 20 to move across the cutaway portions in the members 22 and 30 and will hold the strand of hair therein. Further rotation of the member 15 causes the cutaway portion 18 thereof to move between the bottoms of the members 22 and 30. It also causes the wide outer end of a slot 19 to gather in the hair and to move around the strand of hair. Further movement of member 15 causes the narrow portion of the slot 19 to move around the strand of hair until it is finally positioned between the outer wall of said slot and the inner edges of the cutaway portions 27 and 34 of members 22 and 30. Thus, the lock of hair will be securely held between the member 15 and the members 22 and 30. The opening extending entirely through the gripping device first completely encloses the hair and then rotation of member 15 causes it to be gripped therein. Because of the spiral slot 19 which is wide at its outer end and gradually decreases in width towards its inner end, means is provided for accommodating different sized locks of hair.

The member 30 is further provided with an upwardly extending hub portion 36. This hub portion 36 is adapted to have a coil spring 37 mounted in surrounding relation thereto. One end 38 of this spring, passes into a socket formed in said hub so that the spring is secured thereto. The other end 39 of the spring is free and abuts against the bottom of the cup-shaped member 30. The hub member 36 with the spring 37 in surrounding relation thereto, is adapted to fit within the socket 13 formed in the lower end of the mandrel 1. As will be understood hereinafter, this mechanism permits rotation of the mandrel 1 in a certain direction on the shaft 1 so that the hair may be tightened on the mandrel but precludes rotation of the mandrel in the opposite direction to prevent the hair from becoming loose thereon.

As previously stated, the upper end of the shaft 14 extends a considerable distance above the upper end of the cylindrical extension 4 on the mandrel 1. This upper end of the shaft 14 is provided with a squared portion 40 and a threaded portion 41. The squared portion 40 is adapted to

receive a gear 42 having a squared opening 43 extending therethrough. It will be obvious that rotation of this gear will cause rotation of shaft 14. The gear 42 is provided with a cylindrical extension 42' on the lower end thereof which is devoid of gear teeth. The upper end of the extension 4 on the mandrel 1 is also provided with a portion 42a above the gear member 11 which is also devoid of gear teeth.

A sleeve member 44 is mounted on the extreme upper end of my device and this sleeve is adapted to serve as a clutch member for rotating gear 42, and consequently, shaft 14 or for engaging teeth 11, and consequently, rotating mandrel 1. This sleeve is adapted to be slipped over the gear 42 and teeth 11 and is provided with an annular rack surface 45 disposed on the inner surface thereof. A nut 46 is adapted to cooperate with the upper threaded end 41 of the shaft 14 to prevent removal of the sleeve 44 and to secure other parts of my device together. As will be obvious from the drawings, this nut fits within the sleeve and the rack surface 45 formed therein will cooperate with the nut to prevent removal of the sleeve. The sleeve 44 is provided with lugs 44' on the outer surface thereof, which facilitate rotation of this sleeve.

When the sleeve is in the position shown in Figure 5, if it is rotated it will not serve any function inasmuch as the rack surface 45 will lie over the portion 42' of the gear 42 and the portion 42a of the cylindrical extension 4 of the mandrel. However, if it is moved downwardly from the position shown in Figure 5, to the position shown in Figure 6, the rack member 45 will engage with the teeth 11. Thereafter, rotation of sleeve 44 will cause rotation of the mandrel 1 independent of the shaft 14. If the sleeve is then moved upwardly to the position shown in Figure 7 it may be rotated to cause rotation of the shaft 14 and consequently rotation of the member 15 on the lower end thereof. Thus, the clutch member may be operated to cause the gripping mechanism on the lower end of the device to be operated or to rotate the mandrel 1 which is adapted to cause tightening of the hair thereon as will be herein-after apparent.

When the mandrel 1 is rotated in a counter-clockwise direction, as indicated by the full line arrows in Figure 4, through the medium of the sleeve 44 and teeth 11, the spring 37 in the socket 13 formed in the lower end thereof will tend to become smaller and permit rotation of the mandrel. However, if the mandrel is rotated in a clockwise direction, as indicated by the dotted arrows in Figure 4, the spring 37 will tend to become larger in diameter and to more firmly contact with the walls of the socket 13, so that rotation of the mandrel relative to the hub 36 of member 30 is prevented, since the spring is secured to the said hub. The member 30 will be precluded from rotating relative to member 22 by means of the slot 29 in member 22 and the cooperating key 35 on member 30. The member 22 will be gripped by the fingers during rotation of the mandrel. Thus, rotation of the mandrel in one direction is permitted while rotation in the opposite direction is precluded. As will be understood hereinafter, this makes possible the tightening of the hair on the mandrel and maintaining it in stretched position by locking the mandrel in adjusted position. Furthermore, with this mechanism all parts of the strand of hair are subjected to a substantially uniform tension.

The lower end of my device may be provided

with a disk of felt 52 (Figures 9 to 13) or of other material which will not readily conduct heat so that the lower end of my hair waving device will not contact with the head of the person being operated upon.

In the operation of my device, as shown in Figure 9, the free end of the hair is placed between the mandrel 1 and the member 7. The member 7 is then swung down over the mandrel and held thereon by the finger and thereby grips the hair on such mandrel. Then the entire device is rotated in a counter-clockwise direction indicated by the arrow in Figure 9 until all the hair is wound around the mandrel and the outer surface of the member 7, as shown in Figure 10. Then the portion of the lock of hair adjacent the scalp is inserted into the gripping mechanism on the lower end of the device and such mechanism is operated to tightly grip that portion of the hair. This gripping mechanism is operated by pulling the sleeve member 44 to its uppermost position (Figure 10) and then rotating it in a clockwise direction indicated by the arrow to cause the member 15 of the gripping mechanism to rotate 25 relative to members 22 and 30 and thereby grip the hair therein.

It is then desirable to tighten the hair on the mandrel so that it will be stretched thereon. To do this the member 22, at the lower end of my device, is gripped by the fingers as shown in Figure 11. The sleeve member 44 is then moved downwardly as far as possible and rotated in a counter-clockwise direction indicated by the arrows, (Figure 11), which will cause the mandrel 35 to rotate on shaft 14. Since the lock of hair is secured adjacent the lower end of the device by the gripping mechanism and since the free end of the hair is secured between the member 7 and the mandrel and the hair is wound on the mandrel 40 in a counter-clockwise direction, rotation of the mandrel in a counter-clockwise direction will cause tightening of the hair thereon. Furthermore, this will cause uniform tensional stresses to be imparted to all portions of the lock of hair. 45 Rotation of the mandrel 1 in a reverse direction will be prevented by the spring 37 as previously described.

When the hair is properly positioned on the device, a tube 47 is placed thereover, as shown in Figure 12. This tube is adapted to contain felt, or other such material, which is saturated with hair-waving fluid. This tube 47 is crimped at its upper end so that it tightly fits around my hair-waving device. The tube is also provided with 55 openings 48 in its upper end to allow escape of vapors therefrom.

A heater 49 of any suitable form may be provided and this heater is adapted to receive the hair-waving device with the tube 47 thereon. The heater 49 preferably has a cap member 50 mounted on the upper end thereof, having a duct 51 formed therein so that the vapors may escape therefrom.

After the hair has been properly treated, the 65 various parts of my device are adjusted to release the hair therefrom. To do this, the collar 5 is preferably moved upwardly which will cause upward movement of the member 7 on the mandrel 1. Movement of the member 7 upwardly 70 causes the lower end thereof to move away from the cup-shaped member 30 and to draw most of the hair out of such member, and causes the lock of hair to be wound in a spiral path around the lower end of the mandrel. Then the gripping mechanism may be readily operated to release its

grip on the lower portion of the lock of hair and this lock of hair may then be readily slipped therefrom. The hair may then be unwound from the device by merely turning the entire device in a direction opposite to the arrows in Figure 9.

It will be understood from the above description that I have provided a hair-waving device having many advantageous features. This device is comparatively simple and inexpensive to manufacture and is very effective for the purpose intended. Furthermore, the means for gripping the hair adjacent the scalp and for securing it on the mandrel is easily operated and will not injure the hair.

Another advantageous feature of my invention 15 is the fact that it is provided with means for tightening the hair on the mandrel of such type as to be easily operated and which will subject the hair to uniform tensional stresses and will not subject any given portion of the hair to any 20 excessive strains. Still another advantageous feature of my invention is the fact that this single hair-waving device may be used for producing any of the various types of waves, this being possible because of the shape of mandrel 1 and member 7 and because of the relative adjustability of these two members.

Another advantageous feature of my invention is the fact that it is of such a structure as to be extremely light in weight. Furthermore, because 30 of the structure of the various parts of my device a lock of hair of any length may be properly wound thereon.

Having thus described my invention, what I claim is:

1. A hair-waving device comprising a mandrel having a central portion of small cross-section and gradually increasing in size towards its ends, means for securing hair to said mandrel, said means comprising a member adapted to fit over 40 said mandrel, said means being adjustable longitudinally of said mandrel and swingable between operative and inoperative positions.

2. A hair-waving device comprising a mandrel having a central portion of small cross-section and gradually increasing in size towards its ends, a shaft extending through said mandrel, means adjacent the lower end of said mandrel for gripping the hair adjacent the scalp, means for securing the free ends of the hair to said mandrel, said means comprising a member which is longitudinally adjustable on said mandrel and swingable between operative and inoperative positions, said member being of such a shape that it will firmly embrace said mandrel when in operative position to grip the free ends of the hair and being adapted to rotate therewith, and means adjacent the upper end of said device and adjustable in such a manner that it may be used for operating said gripping means on the lower end of 60 said mandrel, or for rotating said mandrel on said shaft in one direction, and means for precluding rotation of said mandrel in the opposite direction.

3. A hair-waving device comprising a mandrel 65 having a central portion of small cross-section and gradually increasing in size towards its ends, a shaft extending through said mandrel, means adjacent one end of said mandrel for gripping the hair adjacent the scalp, means for securing 70 the free ends of the hair to said mandrel, said means comprising a member which is adjustable on said mandrel between operative and inoperative positions, said member being of a shape similar to said mandrel, so that it will firmly embrace 75

- 5 said mandrel when in operative position to grip the free ends of the hair and so that the hair wound around said mandrel will pass over said member and means adjacent the outer end of said device and adjustable in such a manner that it may be used for operating said gripping means or for rotating said mandrel on said shaft in one direction, and means for precluding rotation of said mandrel in the opposite direction.
- 10 4. A hair-waving device comprising a mandrel having a central portion of small cross-section and gradually increasing in size towards its ends, means adjacent the lower end of said mandrel for gripping the hair adjacent the scalp, means for 15 securing the free ends of the hair to said mandrel, said means comprising a member adapted to embrace said mandrel and swingable between operative and inoperative positions, and means adjacent the upper end of said mandrel and adjustable in such a manner that it may be used for operating said gripping means or rotating said mandrel.
- 15 5. A hair-waving device comprising a mandrel, a shaft extending through said mandrel, means secured to the lower end of said shaft and adapted to grip the hair adjacent the scalp, means adjacent the upper end of said mandrel and adjustable in such a manner that it may be used for rotating said shaft to operate said gripping means 20 or to rotate said mandrel in one direction, means for precluding rotation of said mandrel in the opposite direction, and means for securing the free ends of the hair to said mandrel, said means comprising a member which is longitudinally adjustable on said mandrel and swingable between operative and inoperative positions.
- 25 6. A hair-waving device comprising a mandrel, a shaft extending through said mandrel, means connected to the lower end of said shaft and adapted to grip the hair adjacent the scalp, means adjacent the upper end of said mandrel and adjustable in such a manner that it may be used for rotating said shaft to operate said gripping means or to rotate said mandrel in one direction, means for precluding rotation of said mandrel in the opposite direction, and means for securing the free ends of the hair to said mandrel.
- 30 7. A hair-waving device comprising a mandrel, means adjacent the lower end of said mandrel and adapted to grip the hair adjacent the scalp, means adjacent the upper end of said mandrel and adjustable in such a manner that it may be used for operating said gripping means, or for rotating said mandrel in one direction, means for precluding rotation of said mandrel in the opposite direction, and means for securing the free ends of the hair to said mandrel.
- 35 8. A hair-waving device comprising a mandrel, means adjacent one end of said mandrel and adapted to grip the hair adjacent the scalp, a clutch member adjacent the opposite end of said mandrel and adjustable in such a manner that it may be used for rotating said mandrel in one direction or for operating said gripping means without rotating said mandrel in said direction, and means for precluding rotation of said mandrel in the opposite direction.
- 40 9. A hair-waving device comprising a mandrel, means adjacent one end of said mandrel and adapted to grip the hair adjacent the scalp, and a clutch member adjacent the opposite end of said mandrel and adjustable for rotating said mandrel or for operating said gripping means without rotating said mandrel.

10. A hair-waving device comprising a mandrel on which the hair is adapted to be wound, means for securing the free ends of the hair to the mandrel, said means comprising a member longitudinally adjustable on said mandrel, said member being mounted in such a manner that it may be swung between operative and inoperative positions, and means for precluding relative rotation between said mandrel and said member.

11. A hair waving device comprising a mandrel on which the hair is adapted to be wound, means for securing the free ends of the hair to the mandrel, said means comprising a member swingable between operative and inoperative positions, said member being adapted to partially enclose said mandrel when in an operative position, and said member being longitudinally adjustable of said mandrel.

12. A hair waving device comprising a mandrel on which the hair is adapted to be wound, means for securing the free ends of the hair to said mandrel, said means comprising a member longitudinally adjustable on said mandrel, and means for precluding relative rotation between said mandrel and said member at all times.

13. A hair-waving device comprising a mandrel upon which the hair is to be wound, means for securing the free end of a strand of hair to said mandrel, means adjacent the lower end of said mandrel and adapted to grip the hair at a point closer to the scalp, said gripping means being of such a type that even after the free end of the said strand of hair has been secured to the mandrel, the lower end of the said strand near the scalp may be slipped into said gripping means, means adjacent the upper end of said mandrel for operating said gripping means, and means adjacent the upper end of said mandrel for rotating said mandrel in one direction and means for precluding rotation of said mandrel in the opposite direction.

14. A hair-waving device comprising a mandrel upon which the hair is adapted to be wound, means for securing the free end of a strand of hair to said mandrel, means adjacent the lower end of said mandrel for gripping the strand of hair at a point closer to the scalp, said gripping means having an open-ended slot into which the strand of hair may be slipped even after the free end thereof is secured to said mandrel, means adjacent the upper end of said mandrel for operating said gripping means, means adjacent the upper end of said mandrel for rotating said mandrel in one direction, and means for precluding rotation of said mandrel in an opposite direction.

15. A hair-waving device comprising a mandrel upon which the hair is to be wound, means for securing the free end of a strand of hair to said mandrel, means adjacent the lower end of said mandrel for gripping a strand of hair at a point closer to the scalp, said means comprising a plurality of members rotatable relative to each other, said members having open-ended slots adapted to receive the strand of hair and being of such a type that said strand may be slipped into said gripping means even after the free end thereof is secured to said mandrel, means adjacent the upper end of said mandrel for operating said gripping means to cause relative rotation of said members so that the strand of hair will be gripped thereby, and means for permitting rotation of said mandrel in one direction and for precluding rotation thereof in an opposite direction.

16. A hair-waving device comprising a mandrel upon which the hair is to be wound, means for securing the free end of a strand of hair to said mandrel, means adjacent the lower end of said mandrel for gripping the strand of hair adjacent the scalp, said gripping means being of such a type that the strand of hair may be slipped therein even after the free end thereof is secured to said mandrel, means adjacent the upper end of said mandrel for operating said gripping means to cause it to grip said strand of hair, and means for permitting rotation of said mandrel in one direction and for precluding rotation thereof in the opposite direction.
17. A hair-waving device comprising a mandrel upon which the hair is to be wound, means for securing the free end of a strand of hair to said mandrel, said means comprising a member swingable between operative and inoperative positions and adapted to clamp the hair to the mandrel when in operative position, means adjacent the lower end of said mandrel for gripping the strand of hair at a point closer to the scalp, said means comprising a plurality of members rotatable relative to each other, said members having open-ended slots adapted to receive the strand of hair so that said strand of hair may be slipped into said gripping means even after the free end thereof is secured to said mandrel, means for operating said gripping means to cause relative rotation of said members so that the said strand of hair will be gripped thereby, and means for permitting rotation of said mandrel in one direction and for precluding rotation thereof in an opposite direction.
18. A hair-waving device comprising a mandrel upon which the hair is to be wound, means for securing the free end of a strand of hair to said mandrel, means adjacent the lower end of said mandrel for gripping the strand of hair at a point closer to the scalp, said means comprising a plurality of superimposed members adjustable relative to each other, one of said members having an open-ended slot of such a type that the strand of hair may be slipped into said gripping means even after the free end thereof is secured to said mandrel, means for operating said gripping means to cause relative movement between said members so that the strand of hair will be gripped in said slot, and means for permitting rotation of said mandrel in one direction and for precluding rotation thereof in an opposite direction.
19. A hair-waving device comprising a mandrel upon which the hair is adapted to be wound, means for securing the free end of a strand of hair to said mandrel, means adjacent the lower end of said mandrel for gripping the strand of hair closer to the scalp, said gripping means being of such a type that even after the free end of the strand of hair is secured to said mandrel, the said strand may be slipped into said gripping means, said gripping means being permanently secured to said mandrel in such a manner that it cannot be separated therefrom, and means for permitting rotation of said mandrel in one direction and for precluding rotation thereof in an opposite direction.
20. A hair-waving device comprising a mandrel upon which the hair is adapted to be wound, means for securing the free end of a strand of hair to said mandrel, means adjacent the lower end of said mandrel for gripping the strand of hair closer to the scalp, said gripping means being of such a type that the strand of hair may be slipped therein even after the free end thereof is secured to said mandrel, means adjacent the upper end of said mandrel for permitting rotation of said mandrel in one direction and for precluding rotation thereof in the opposite direction.
21. A device of the character described comprising a mandrel formed with an axially extending bore, a rod extending through the bore and rotatable therein, a housing rotatably engaged with the lower end of said mandrel and formed with a hair receiving recess, a keeper rotatable in said housing and moved into and out of a hair gripping position by rotation of said rod, and means for selectively rotating the rod and mandrel relative to the housing and each other.
22. A device of the character described comprising a mandrel formed with an axially extending bore, a rod extending through the bore and rotatable therein, means for connecting the mandrel to a lock of hair including a stationary hair receiving element and a hair gripping element moved into and out of a gripping position by turning said rod, said mandrel being rotatable relative to the hair receiving element, and means for selectively rotating the rod and mandrel.
23. A device of the character described comprising a mandrel, means for connecting said mandrel with a lock of hair disposed at one end of the mandrel including a movable hair gripper having an operating element extending longitudinally of the mandrel and common actuating means for the mandrel and said operating means selectively movable into engagement with the same.
24. A device of the character described comprising a mandrel, means for connecting said mandrel with a lock of hair disposed at one end of the mandrel including a movable hair gripper having an operating element extending longitudinally of the mandrel and an actuating element slidable longitudinally of the mandrel and operating element for selective interlocked engagement with the same.
25. A device of the character described comprising a mandrel, means for connecting said mandrel with a lock of hair disposed at one end of the mandrel including a movable hair gripper having an operating rod extending axially through the mandrel, the mandrel and rod being provided with clutch elements, and an actuating element slidable longitudinally of the mandrel and rod and having clutch elements selectively engaged with the clutch elements of the mandrel and rod by sliding movement of the actuating element.
26. A device of the character described comprising a mandrel, means for connecting said mandrel with a lock of hair including a hair gripper and an operating element for the same, and actuating means common to both the mandrel and said operating element.
27. A device of the character described comprising a mandrel, means for connecting said mandrel with a lock of hair including a hair gripper and an operating element for the same, the mandrel and operating element being rotatable relative to each other, and an actuating element for the mandrel and operating element selectively engageable with the same.
28. A device of the character described comprising a rotatable mandrel and a hair gripper having a rotatable operating element concentric with the mandrel and common means for selectively engageable with the same.

lectively rotating the mandrel and operating element.

29. A device of the character described comprising a rotatable mandrel, a hair gripper at 5 one end of said mandrel, an operating element for said gripper, and common actuating means for the mandrel and operating element.

30. A device of the character described comprising a rotatable mandrel and a hair gripper 10 having an operating element movable relative to the mandrel, and common actuating means for the mandrel and said operating element.

31. A device of the character described com-

prising a rotatable mandrel, a hair gripper at one end of said mandrel, and an actuating element for the mandrel and hair gripper at the other end of the mandrel.

32. A device of the character described comprising a rotatable mandrel, a hair gripper at one end of said mandrel having an element movable 5 into and out of a gripping position and means at the other end of the mandrel for selectively actuating the mandrel and movable element of 10 the gripper.

PETER SANTURELLO.
